(57) **CLAIM**

The ornamental design for a developer supplying container, as shown.

DESCRIPTION

FIG. 1 is a front view of a developer supplying container showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

PATENT NO. : Des. 530,359 S
APPLICATION NO. : 29/254093
DATED : October 17, 2006
INVENTOR(S) : Tetsuo Isomura et al.

Page 1 of 9

It is certified that error appears in the above-identified patent and that said Letters Patent is hereby corrected as shown below:

The title page should be deleted and substitute therefor the attached title page.

Drawings:

Delete drawing sheets 1-7, and substitute therefor the drawing sheets, consisting of Figs. 1-7 as shown on the attached pages.

Signed and Sealed this

Twenty-sixth Day of May, 2009

JOHN DOLL
Acting Director of the United States Patent and Trademark Office
